UNITED STATES PATENT OFFICE.

WILLIAM L. CAWTHON, OF HARPERS FERRY, VIRGINIA.

RAILROAD-SWITCH LOCK.

Specification of Letters Patent No. 17,492, dated June 9, 1857.

To all whom it may concern:

Be it known that I, WILLIAM L. CAWTHON, of Harpers Ferry, in the county of Jefferson and State of Virginia, have invented a new and useful Improvement in Locks for Railroad-Switches; and I do hereby declare that the following is a full, clear, and exact description of the construction and operation of the same, reference being had 10 to the annexed drawing, forming part of this specification, in which—

Figure 1 is a view of switch lever and post with my improved lock attached. Fig. 2 is an inside view of lock detached. Fig. 3 15 is a top view of lock detached.

Similar characters of reference in the several figures denote the same part.

The object of my invention is to provide a simple and secure mode of securing the 20 levers of railroad switches. The ordinary method of doing which, is to hold the lever under a hasp secured to the post by a padlock.

My invention consists in providing a lock, 25 the plate of which shall be flush with the face of the post, and which shall have a curved arm hinged thereto, the hollow of which arm will hold the switch lever against the post; the bolt of the lock securing the 30 arm as will be hereinafter set forth.

In the drawing P is the post and B the switch lever.

L is the lock, the plate of which is flush

with the face of the post when attached thereto. On the face of the lock is a projection *a*, to which is hinged an arm *A*, having a curve *b* to receive the lever *L* and a curve *C* to afford the means of moving said arm. At *d* the arm is provided with a lip *f*, which passes through the plate and receives the 35 bolt *h*. This bolt runs diagonally as shown in Fig. 2, and is moved by a key inserted in the key hole *g*.

The operation of the improvement is as follows: The lever is confined against the 40 post, as shown in Fig. 1. The turning of the key releases the attachment of the arm *A* which when swung back, leaves the lever free to drop.

For simplicity of construction and facility 45 of operation this lock is far superior to the devices now employed to secure the switch levers.

I claim—

The arrangement upon the lock plate of 50 the curved securing arm *A* constructed and operating as described for the purpose specified.

In testimony whereof, I have hereunto signed my name before two subscribing witnesses.

WM. L. CAWTHON.
